UNITED STATES PATENT OFFICE.

WILLIAM ENSLEY LAWHORN, OF CARUTHERSVILLE, MISSOURI.

EQUALIZING DEVICE FOR VEHICLES.

SPECIFICATION forming part of Letters Patent No. 650,845, dated June 5, 1900.

Application filed March 21, 1900. Serial No. 9,568. (No model.)

To all whom it may concern:

Be it known that I, WILLIAM ENSLEY LAWHORN, a citizen of the United States, residing at Caruthersville, in the county of Pemiscot 5 and State of Missouri, have invented a new and useful Equalizing Device for Vehicles, of which the following is a specification.

The invention relates to improvements in equalizing devices for vehicles.

One object of the present invention is to improve the construction of equalizing devices for spring-supported bodies and to provide a simple, inexpensive, and efficient device designed to be applied to wagon-bodies, 15 car-bodies, and the bodies of other vehicles or conveyances and capable of equalizing the weight and distributing the same equally to all of the springs supporting a body.

A further object of the invention is to provide a device of this character which will be positive and reliable in its operation and which will permit a body to move freely without binding.

The invention consists in the construction 25 and novel combination and arrangement of parts hereinafter fully described, illustrated in the accompanying drawings, and pointed out in the claim hereto appended.

In the drawings, Figure 1 is a longitudinal 30 sectional view of a wagon provided with equalizing devices constructed in accordance with this invention. Fig. 2 is a transverse sectional view of the same.

Like numerals of reference designate corresponding parts in both figures of the drawings.

11 designate a pair of transversely-disposed equalizing-levers fulcrumed at their lower ends on pivots 2 and diverging upwardly and 40 disposed at an inclination, as clearly shown in Fig. 2 of the accompanying drawings, when the body 3 of the vehicle to which the device is applied is not subjected to any weight. The lower ends of the equalizing-levers are 45 arranged within a casing 4 and are provided with segmental heads 5, having teeth 6, meshing with each other and arranged concentric with the pivots 2, whereby the levers 1 are caused to oscillate simultaneously. The levers 50 by being geared together in this manner are not only caused to oscillate simultaneously, but are effectually prevented from

binding. The casing 4, which may be of any desired construction, is composed of two sides of approximately-rectangular shape, one of 55 the sides being extended beyond the other and secured to the adjacent axle by suitable fastening devices.

The upper ends of the levers are connected with the body of the vehicle by upwardly-diverging links 7, pivoted or hinged at their lower ends to the outer ends of the levers and hinged at their upper ends 8 to the body 3. The lower ends of the links or rods 7 may be pivoted to the transversely-disposed equalizing-levers in any suitable manner, but are preferably bifurcated at 9, as clearly shown in Fig. 1, to receive the levers 1. The upper ends 8 of the inclined links or rods 7 are perforated and have staples 10 linked into the 70 perforations, whereby the links or rods are secured to the body 3.

The equalizing devices are shown applied to a wagon in the accompanying drawings, and their casings are secured to the front and 75 rear portions of the running-gear, the rear equalizing device being mounted on the rear axle 11 and the front equalizing device being secured to the sand-board or bolster 12; but it may be mounted on any portion of the 80 running-gear which does not turn with the front axle. Ordinary leaf-springs are illustrated in the accompanying drawings for supporting the body 3; but the equalizing devices are equally applicable to railway-cars, 85 coaches, and any other spring-supported vehicle-bodies, and the number of equalizing devices employed may be varied to suit the character of the vehicle, the weight to be sustained by the body, and the strength of the 90 supporting-springs. They enable the weight to be distributed equally to the springs, and one side of the body cannot be depressed to any greater extent than the other, even should a weight sufficient to entirely compress the 95 springs be applied to one side. The levers form flexible connections between the body and the axle-truck or other support, and they do not in any manner interfere with the resiliency of the springs and are equally applicable to light road-vehicles and to heavy railway-cars. The toothed segments or cogs at the inner ends of the equalizing-levers may be formed integral with them, as illustrated in 100

Fig. 2 of the accompanying drawings, or they may be secured to or connected with the levers in any other suitable manner, and the device is also applicable to stationary spring-supported bodies, as well as to those of vehicles and conveyances.

It will be seen that the equalizing device is simple and comparatively inexpensive in construction, that it possesses great strength and durability, and that it will permit a free vertical play of the vehicle-body and will not bind when any portion of the body is subjected to a heavy weight.

What is claimed is—
15 The combination with a spring-supported

body, of an equalizing device comprising a pair of upwardly-diverging equalizing-levers fulcrumed at their lower ends and provided thereat with meshing cogs, and the links diverging upwardly from the upper ends of the equalizing-levers and pivotally connected to the same and to the said body, substantially as described.

In testimony that I claim the foregoing as my own I have hereto affixed my signature in 25 the presence of two witnesses.

WILLIAM ENSLEY LAWIIORN.
